TOY SOUVENIR BLOCK

Carl H. Dalsgaard, R.F.D. 5, Driftwood Point,
Danbury, Conn. 06810

Filed Aug. 18, 1965, Ser. No. 86,622

Term of patent 14 years

(Cl. D34—15)

I claim:

The ornamental design for a toy souvenir block, as shown.
